[57] CLAIM

The ornamental design for a mounting bracket, as shown.

DESCRIPTION

FIG. 1 is a side elevational view of a mounting bracket showing my new design;

FIG. 2 is a side elevational view of the side opposite that shown in FIG. 1;

FIG. 3 is a top plan view thereof;

FIG. 4 is a bottom plan view thereof;

FIG. 5 is a right-end elevational view thereof;

FIG. 6 is a left-end elevational view thereof; and

FIG. 7 is a perspective view thereof.
